UNITED STATES PATENT OFFICE.

OWEN DAVID LUCAS, OF LINDEN GARDENS, LONDON, ENGLAND, ASSIGNOR TO V. M. L. EXPERIMENTAL LIMITED, OF WESTMINSTER, LONDON, ENGLAND, A BRITISH COMPANY.

SHELL.

Original application filed June 20, 1922, Serial No. 569,732. Divided and this application filed July 28, 1922. Serial No. 578,167.

To all whom it may concern:

Be it known that I, OWEN DAVID LUCAS, a subject of the King of Great Britain, residing at 49 Linden Gardens, in the county 5 of London, England, have invented certain new and useful Improvements in or Relating to Shells, of which the following is a specification.

This case is a division of application Serial No. 569,732, filed June 20, 1922.

This invention relates to shells intended to be projected into the air from an unrifled gun on the ground for signaling to or guiding aircraft by means for example of a light 15 or smoke emitting device suspended from a parachute which, with the said device, is thrown from the shell by means of an expelling charge, the said shell being made in three main parts, viz, a base, a nose or head 20 and a connecting tubular body to which the base and the nose or head are connected in such a manner that when the expelling charge is ignited either the base or the nose or head will be forced off and the other of these 25 two parts will remain connected to the tubular body.

According to the present invention the base or the nose whichever is intended to remain attached to the tubular body is connected to the latter by means of a portion 30 of the body which is pressed or spun into a circumferential recess in the base or the nose, the nose or the base whichever is intended to be forced off by the expelling charge is connected to the body by one or more shearing pins, and the base member carries the igniting device for the expelling charge, which device is ignited by the flame 35 in the gun barrel.

In order that the said invention may be clearly understood and readily carried into effect the same will now be described more fully with reference to the accompanying drawings, in which:—

Figure 1 is an axial section showing a form of the invention in connection with a shell of the parachute signal type.

Figure 2 is a view similar to Figure 1 showing the invention employed in connection with a shell of the star or smoke pellet type, and

Figure 3 is a section taken on the line 2-3 of Figure 2.

A is the base, B is the nose or head and C is the tubular body which at one end is 55 pressed or spun into a circumferential recess in the base A or the nose or head B and at its other end is connected to the nose or head or to the base by small pins b— and bayonet slots there being for example three 60 such pins and slots. D is the expelling charge and E is the Bickford fuse ignited by the igniting or fuse device. The pins b— are made of such diameter and material that when the bursting charge is ignited they 65 will be sheared and the body C will be left connected to the base A or to the nose or head B. F is a cup-shaped gas-check carried by the base A.

Referring to Figure 1, B¹ is the parachute 70 packed within the hollow nose B and C¹ is the container for the smoke or flame producing composition, which container is arranged within the tubular body C and is connected to the parachute by means of a 75 wire loop C² and a swivel C³. To the rear of the said container is a wood block C⁴ which is recessed at C⁵ to receive lead shot. This shot is intended to keep the total weight 80 of the shell constant despite differences in the weight of the container C¹ when loaded with different compositions, the quantity of shot placed in the recess varying with such differences in weight. The container C¹ is separated from the parachute B¹ and from 85 the wood block C⁴ by wads and washers as shown. The rear part of the said wood block is recessed to receive the expelling charge D which is ignited by means of the Bickford fuse E arranged in the base A. 90 The composition in the container C¹ is ignited by a quick-match G. When the expelling charge D is ignited, the block C⁴ and the container C¹, are pressed forward 95 and the nose B is forced off through the intermediary of a wood ring C⁶, the pins b— being sheared during this operation. The block, container and parachute are thus expelled and the block falls away thus leaving the container suspended by the parachute. 100 The Bickford fuse E in the base A is ignited from the flame resulting from the ignition of the propelling charge in the gun when the latter is fired the flash passing through the small hole f¹ in the nut F¹ and igniting a 105 compressed powder pellet F² the flame from

which passes to the Bickford fuse E, through a small hole f* in a plug F* screwed into the base A.

In the construction of star or smoke pellet shells shown by Figures 1 and 2, the stars or pellets K, K— are arranged end to end in separate tubes K², K² of which there may be three for example as shown. These stars or pellets are ignited by quick-match leads 10 K¹ so arranged that the stars or pellets are ignited before they are ejected by charges (one of which is shown at D⁰) the star or pellet in each tube that is first ejected being ignited before the other in that tube.

15 The aforesaid gas-check F for the shell is connected to the base A by a nut F¹ screwed on the rear end of the casing H¹. This gas-check is made of thin metal and is shaped as shown so that the gases in the gun 20 barrel force the sides against the interior of the barrel, it being understood that the latter is unrifled. The recess for the Bickford fuse E is closed by two washers E¹, E², against the rear one of which the base of 25 the gas-check F bears.

What I claim and desire to secure by Letters Patent of the United States is:—

1. A shell comprising in combination, a tubular body, a base member, a nose member, and a cupped member constituting a 30 gas check within a gun barrel, means for securing said cupped member to the base member, a fuse igniting substance carried

within said cupped member securing means, and a passageway in said cupped member 35 securing means, whereby the fuse-igniting substance will be exposed to flame in the gun barrel.

2. A shell comprising in combination, a tubular body, a base member, a nose member, and a cupped member constituting a gas check within a gun barrel, means for securing said cupped member coaxially of the base member, a fuse igniting substance carried within said cupped member securing 40 45 means, and a passageway in said cupped member securing means, whereby the fuse-igniting substance will be exposed to flame in the gun barrel.

3. A shell comprising in combination, a tubular body, a base member, a nose member, a portion of said body pressed into a circumferential groove in one of said members, a shearing pin connecting the other of said members to said body, an expelling 50 55 charge, a cupped member constituting a gas check within a gun barrel, means for securing said cupped member to the base member, a fuse-igniting substance carried within said cupped member securing means, and a passageway in said cupped member securing means, whereby the fuse-igniting substance will be exposed to flame in the gun barrel.

OWEN DAVID LUCAS.
